ADJUSTABLE INFANT'S CHAIR

Earl F. Hamilton, Columbus, Ind., assignor to Hamilton Cosco, Inc., Columbus, Ind., a corporation of Indiana

Filed Aug. 31, 1960, Ser. No. 62,073

Term of patent 14 years

(Cl. D15—1)

FIG-3

FIG. 1 is a front elevation of an infant's chair showing my new design and showing the same in adjusted position for use as a baby jumper;

FIG. 2 is a side elevation of the chair shown in FIG. 1;
FIG. 3 is a rear elevation of the chair shown in FIG. 1;
FIG. 4 is a perspective view of the chair shown in FIG.

1; and

FIG. 5 is a perspective view of the chair shown in FIG. 1, but showing the same in adjusted position for use as a stationary tilt chair.

I claim:

The ornamental design for an adjustable infant's chair, as shown.
